AUTOMATIC RECLOSED CIRCUIT BREAKER SYSTEM

Werner Kaufmann, Berlin-Siemensstadt, Germany, assignor to Westinghouse Electric & Manufacturing Company, East Pittsburgh, Pa., a corporation of Pennsylvania

Application November 15, 1940, Serial No. 365,825
In Germany October 6, 1939

19 Claims. (Cl. 175—294)

This invention relates to circuit interrupters and, more particularly, to high capacity circuit interrupters for use in electrical transmission or distribution systems.

It is a known practice to use in high-voltage circuits certain switching arrangements for the purpose of suppressing any fault-condition that develops in such a circuit in the form of an arc in air or flash-over. Such switching arrangements, which are not designed to remain permanently in the "off" position, function by temporarily interrupting the flow of power towards the point at which such a fault-condition has developed. These switching arrangements called "short-circuit suppressors," reclose almost immediately after having interrupted the circuit. One type of such short circuit suppressor is equipped with a circuit interrupter for interrupting the circuit and with a switch in parallel with the interrupter for reclosing the circuit. In other designs, however, the same interrupter that is being used for interrupting the circuit may be employed for the reclosure. For instance, in the case of an interrupter in which the arc is interrupted with the aid of compressed gas, it is feasible to withdraw the movable rod-shaped contact member only up to the point at which this member is in the most favorable position for extinguishing the arc, although for this particular position of the movable contact member the distance between this member and the stationary contact member would not be large enough if the interruption had to be of a permanent nature. And when breakers operating with a nonconductive liquid in the switching chamber are used for suppressing short-circuits, the disconnecting switches with contacts in air that are usually connected in series with such breakers may be omitted. Switching arrangements of the kind to which reference is being made are not, as a rule, capable of use as a disconnecting device to permanently interrupt the circuit since they are not constructed to provide a large enough gap in the open position for this purpose.

Under certain instances, however, switching arrangements of the kind to which reference is being made, in addition to being employed as short-circuit suppressors, have to function occasionally as tie-breakers or as transformer breakers. In such an instance it is advisable to provide breaker arrangements that can be used equally well as disconnecting devices, that is, as devices for permanently interrupting the circuit in which they are employed.

In order to meet the latter requirement with

rather simple means that will nevertheless be sufficiently reliable under operating conditions, the present invention has for an object the provision of a switching arrangement in which the

5 disconnecting switch normally provided in series with the device constituting the short-circuit suppressor is equipped with a remotely controllable operating mechanism which, together with the operating mechanism for the short-circuit suppressor, is so controlled that the closing as well as the opening motion of the disconnecting switch will be caused to take place exactly within the interval of time during which the high-voltage circuit is temporarily interrupted by the 10 short-circuit suppressor.

Another object of this invention is to provide a circuit interrupter having a disconnecting switch which is operable to permanently interrupt the circuit during the time interval when 15 the circuit is momentarily interrupted by the circuit interrupter.

Another object of the invention is the provision of switching apparatus comprising a circuit interrupting device which is automatically operable to interrupt and automatically reclose the circuit, and a disconnecting switch in series therewith to provide for normal opening and closing of the circuit, the operating means of the switch being interlocked with the interrupting device in 20 such a way that the circuit is always interrupted and open at the interrupting device when the switch is operated.

Another object of the invention is the provision of switching apparatus comprising an automatic reclosing circuit interrupting device, a disconnecting switch in series therewith, and operating means operable to open or close the disconnecting switch and to cause the circuit to be temporarily interrupted by the interrupting device whenever the disconnecting switch is operated.

Another object of the invention is to provide a circuit interrupter having an improved operating mechanism which insures complete opening and closing movements of the interrupter.

Another object of the invention is to provide a circuit interrupter or switch having a compressed air operating mechanism with auxiliary air reservoirs for collecting sufficient air under pressure to insure a full stroke if the supply of operating air should be prematurely interrupted.

Another object of the invention is to provide switching apparatus having a plurality of switching devices with a control system which prevents 50 operation of one of said switch devices to open

or closed position, when any one of the remainder of the switch devices is in the closed position.

Another object of the invention is to provide a circuit breaker having an interrupting switch, a reclosing switch, and a disconnecting switch with means controlled by the interrupting switch and by the reclosing switch to suppress movement of the disconnecting switch to open position or to closed position until both the interrupting switch and the reclosing switch are open.

The novel features that are considered characteristic of the invention are set forth in particular in the appended claims. The invention itself, however, both as to structure and operation, together with additional objects and advantages thereof, will be best understood from the following detailed description of one embodiment thereof when read in conjunction with the accompanying drawing, which diagrammatically illustrates switching apparatus embodying the principles of the invention.

Referring to the drawing, 1 indicates a circuit interrupting switch and 2 indicates a circuit closing switch connected in a high capacity circuit in parallel with the interrupting switch 1. A disconnecting switch 3 is connected in the circuit in series with the switches 1 and 2. The interrupting switch 1 is biased in a clockwise or circuit opening direction by a spring 5 having one end connected to an arm 7 movable with the switch 1, and the other end suitably connected to a stationary part of the circuit interrupter. A spring 9 having one end connected to an arm 11 movable with the circuit closing switch 2 and the other end connected to a stationary part biases the closing switch 2 in a clockwise or circuit closing direction. A latch 13 cooperates with a latch member 15 movable with a guided rod 17 to releasably restrain the switch member 1 in closed position, and a guided rod 19 movable with the switch 1 cooperates with the switch member 2 to restrain the switch 2 in open circuit position when the switch 1 is in closed position.

A trip device 21 comprising a trip coil 23 and a cooperating movable core 25 is provided to release the rod 17 and permit the springs 5 and 9, respectively, to open the interrupting switch 1 and close the reclosing switch 2.

The interrupting switch 1 is operated to its closed position, and the reclosing switch 2 is operated to its open position by means of a compressed air device 27 comprising a cylinder 29 and a piston 31 reciprocably movable therein, and which is operatively connected to the operating rod 17. Air or other suitable fluid under pressure is admitted to the cylinder under the control of an electro-magnetically operated control valve 33. The control valve 33 is connected to a suitable source of compressed fluid by a pipe 35, and a pipe 37 conveys the fluid from the valve to the cylinder.

The control valve 33 comprises a U-shaped magnet core 39 having one leg secured to the valve casing 41 and having a winding 43 on the other leg. When the coil 43 is energized, in a manner to be described later, it attracts an armature 45 pivotally mounted on the casing 41 and the armature 45 actuates a pilot valve member 47 to operate a main valve 48 and thereby admit compressed air through the pipe 37 to the cylinder 29.

The disconnecting switch 3 is operated to its open position and also to its closed position by means of an air pressure operated device 49. This device comprises a cylinder 51 within which

5 a piston 53 is reciprocably movable. An operating rod 55 connects the piston 53 to the disconnecting switch member 3. Provision is made to selectively admit compressed air into the cylinder to the left and to the right of the piston 53 in order to open and close the disconnecting switch 3. Two valves 57 and 59 are provided for this purpose and are adapted to be operated by electro-magnets comprising windings 61 and 63 which, when energized, attract their respective armatures 65 and 67 to operate the valves 57 and 59.

10 The interrupter switch 1 is opened and the reclosing switch 2 is closed substantially instantaneously thereafter in response to a fault condition such as an arc short circuit or flashover in the circuit, through the agency of the contacts 75 of a conventional fault relay. When the relay contacts 75 close a circuit is established for 15 energizing the coil 23 of the trip device 21. The circuit may be traced from a source conductor 77 of an auxiliary supply line through a conductor 79, the relay contacts 75, conductors 81 and 83, auxiliary contacts 85 closed when the interrupting switch 1 is closed, conductor 87, coil 23 of the trip device 21, conductors 91, and 93 to a source conductor 95. Energization of the trip coil 23 operates the latch 13 to release the operating rod 17, whereupon the spring 5 moves the 20 interrupting switch 1 to open position and the spring 9 moves the reclosing switch 2 to its closed position thereby immediately reclosing the main circuit.

25 The majority of faults occurring on the transmission line are of a transitory nature and will have disappeared in the brief interval of time between the opening of the switch 1 and the closing of the switch 2, and these switches may then be reset to their normal positions, as shown. 30 The switch 1 is closed and the switch 2 is opened by the compressed air device 27. It was previously stated that air under pressure is admitted to the cylinder 29 by operation of the control valve 33 upon energization of the winding 43. 35 This is effected by manual operation of a resetting switch 97. Operation of the switch 97 closes contacts 99, which establishes a circuit through the coil 43 extending from the conductor 77, through conductors 79 and 101, contacts 40 99, conductor 103, coil 43, and conductor 93 to the conductor 95.

45 Operation of the valve 47 admits air to the cylinder 29 which causes the piston 31 to move to the left, opening the switch 2 and closing switch 1. When the rod 17 is moved toward the left to effect closing of the switch 1, the latch 13 resumes its latching position. The movement of the switch member 1 to closed position is transmitted by the rod 19 to open the switch 2.

50 It was stated previously that the disconnecting switch 3 is both opened and closed by means of the device 49, under control of the electro-magnetically operated valves 57 and 59. These valves are operated under the control of a manually operable switch indicated generally by the reference numeral 105. Manipulation of the switch 105 also effects opening of the interrupting switch 1.

55 The switch 105 comprises three switch blades 107, 109, and 111 operatively connected by means of a tie rod 113, and each electrically connected to the conductor 101. The switch blades 109, 111 and 113 are provided with an operating handle 114 and are operable in both 60 directions as a unit, and each is adapted to co-

operate with two contacts, respectively, 115 and 117, 119 and 121, and 123 and 125.

When it is desired to open the disconnecting switch 3, the handle 114 is moved toward the right, moving the switch blades 107, 109 and 111 toward the left into engagement with contacts 115, 119 and 123, respectively.

Since one of the important features of the invention is to open the disconnecting switch 3 only when both the closing switch 2 and the interrupting switch 1 are open, it is necessary to prevent switch 2 from closing when the trip device 21 is energized. This is effected by energization of a lockout coil 127 comprising a winding 129 and a movable armature 131 adapted, when the winding 129 is energized, to engage a latch member 133 on the end of a rod 135 to prevent closing of the switch member 2.

Operation of the switch 105 to the "off" position establishes three circuits. The first energizes the lockout coil 127 to prevent closing of the switch 2; the second energizes the trip device 21 to effect opening of the interrupting switch 1; and the third prepares a circuit for the coil 61 to effect opening of the disconnecting switch 3 after switch 1 reaches open position.

The first mentioned circuit is traceable from the conductor 77 through conductors 79 and 101, the switch blade 107, contact 115, a conductor 131, coil 129 of the lockout device 127, conductors 89, 91 and 93 to the conductor 95. Energization of the coil 129 engages the armature 131 with the latch 133 and prevents closing of the switch 2.

The second previously mentioned circuit is established by engagement of the switch blade 109 with the contact 119 to energize the trip coil 23 and cause opening of the interrupter switch 1. This circuit is traceable from the conductor 77 through conductors 79 and 101, the switch blade 109, contact 119, a conductor 141, the conductors 81 and 83, auxiliary contacts 85, conductor 87, coil 23 of the trip device 21, conductors 89, 91 and 93 to the conductor 95.

Energization of the trip magnet causes release of the rod 17 and the spring 5 immediately moves the switch 1 to open position. We now have the switch 2 restrained in open position and the switch 1 in open position.

The third previously mentioned circuit extends from the conductor 77, through conductors 79 and 101, switch blade 111, contact 123, a conductor 143, coil 61, conductor 145, auxiliary contacts 147, closed when the switch 2 is open, a conductor 149, auxiliary contacts 151 closed when the switch 1 is open, conductors 91 and 93 to the conductor 95.

The circuit just described energizes the coil 61 which operates the valve 57, admitting compressed air to the left of the piston 53 and causing opening of the switch 3. As the rod 55 moves to open the switch 3, a sliding contact member 153 holds the lockout coil 129 energized until the switch 3 is completely opened, whereupon the contact 153 opens deenergizing the coil 129 which permits the switch 2 to close. The holding circuit for the lockout device 127 extends from the conductor 77 through a conductor 154, the contacts 153, a conductor 156, coil 129, conductors 89, 91 and 93 to the conductor 95.

The sliding contact 153 insures that the switch 2 will be held open, in the event the control switch 105 is prematurely released, until the disconnecting switch 3 is fully opened. When the disconnecting switch reaches its open position, the manual control switch 105 may then be re-

turned to its neutral position. The locking device 127 is thereupon deenergized, and switch 2 is moved to closed position by spring 9.

The interrupting switch 1 and the reclosing switch 2 may now be reset to the normal position shown by operation of the switch 97 in the previously described manner, the disconnecting switch 3 remaining open.

With the switches in this condition, that is, 10 the switch 1 closed, switch 2 open, and switch 3 open, it is necessary, in order to close the disconnecting switch 3 against an open circuit to first open the switch 1.

This is effected by operating the switch 105

15 to the "on" position to engage the switch blades 107, 109, and 111, respectively, with the contacts 117, 121 and 125. This operation of the switch 105 sets up the previously described circuit to

20 energize the lockout relay 127 and also completes the previously described circuit to energize the trip device 21. This results in holding the switch 2 open while the switch 1 is opened by the spring 5.

At the same time, engagement of the switch blade 111 with the contact 125 establishes a circuit for energizing the valve operating coil 63 to effect closing of the disconnecting switch 3. This circuit may be traced from the conductor 77 through the conductors 79, and 101, the switch blade 111, contact 125, a conductor 155, coil 63,

25 conductor 145, auxiliary contacts 147, conductor 149, auxiliary contacts 151 which close when the interrupting switch 1 reaches open position, conductors 91 and 93 to the conductor 95. Operation of the valve 59 by the coil 63 admits compressed

30 air to the right of the piston 53, which now occupies a position in the right-hand end of the cylinder 51, to effect closing of the switch 3. The manual switch 105 may now be released. As the switch 105 moves to its neutral position, the coil 129 of the lockout relay 127 is deenergized, since the contacts 153 opened when the switch 3 closed, permitting the switch 2 to go to its closed position.

35 The interrupting switch 1 may now be closed and the reclosing switch reset to its open position in the previously described manner by depressing the switch member 97 to close contacts 91 which energize the valve operating magnet 43.

It will be seen from the foregoing description 40 that the circuit is always caused to be open at the switches 1 and 2 whenever the disconnecting switch is operated either to closed or to open position.

Auxiliary compression chambers 157 and 159 45 are provided in the cylinder 51 communicating with the cylinder on both sides of the piston 53 to provide a sufficient supply of air under pressure to insure complete opening and closing movements of the disconnecting switch 3 in the 50 event the switch 105 is released prematurely.

What is claimed is:

1. A circuit breaker comprising a circuit interrupting switch biased open, a circuit reclosing switch biased closed and connected in the circuit 55 of the breaker in parallel with said interrupting switch, means for releasably holding the interrupting switch closed and for holding the reclosing switch open, a disconnecting switch connected in the circuit in series with the interrupting switch and the reclosing switch, operating means for opening and closing the disconnecting switch, and control means operable to cause said operating means to open or to close the 60 disconnecting switch and to cause the interrupt-

ing switch and the reclosing switch to be open during operation of the disconnecting switch.

2. A circuit breaker comprising a circuit interrupting switch biased open, a circuit reclosing switch biased closed and connected in the circuit controlled by the breaker in parallel with said interrupting switch, means for releasably holding the interrupting switch closed and for holding the reclosing switch open, additional means for holding the reclosing switch open, a disconnecting switch connected in the circuit in series relation with the interrupting switch and the reclosing switch, operating means for said disconnecting switch, and control means operable to cause release of the interrupting switch and the additional holding means to hold the reclosing switch open and for causing the operating means to open the disconnecting switch after the interrupting switch reaches open position.

3. A circuit breaker comprising a circuit interrupting switch biased open, a circuit reclosing switch biased closed and connected in the circuit in parallel with said interrupting switch, means for releasably holding the interrupting switch closed and for holding the reclosing switch open, additional means for holding the reclosing switch open, a disconnecting switch connected in the circuit in series relation with the interrupting switch and with the reclosing switch, operating means for opening and closing said disconnecting switch, and control means for said circuit breaker for initiating an opening movement of the interrupting switch, for causing the additional holding means to momentarily hold the reclosing switch open when the interrupting switch opens and for causing an opening movement of the disconnecting switch in the time interval during which both the interrupting switch and the reclosing switch are open.

4. A circuit breaker comprising a circuit interrupting switch biased open, a circuit reclosing switch biased closed and connected in the circuit in parallel relation with said interrupting switch, means for releasably holding the interrupting switch in closed position and for holding the reclosing switch in open position, a disconnecting switch connected in the circuit in series relation with the interrupting switch and the reclosing switch, operating mechanism for opening and closing said disconnecting switch, control means operable to cause release of the interrupting switch and to cause the operating mechanism to open the disconnecting switch after the interrupting switch reaches open position, and means controlled by the reclosing switch to prevent opening of the disconnecting switch while said reclosing switch is in closed position.

5. A circuit breaker comprising a circuit interrupting switch biased in opening direction, a circuit reclosing switch biased in closing direction and connected in the circuit controlled by the breaker in parallel relation with said interrupting switch, means for releasably holding the interrupting switch closed and for holding the reclosing switch open, a disconnecting switch connected in the circuit in series relation with said interrupting switch and said reclosing switch, a compressed air operating mechanism for opening and closing the disconnecting switch, control means including a manually operable controller operable to cause an opening operation of the interrupting switch and to cause opening of the disconnecting switch after the interrupting switch reaches open position,

means comprising an air reservoir to insure a complete opening operation of the disconnecting switch in the event of premature return of the controller to inoperative position, and means controlled by the reclosing switch to prevent opening of said disconnecting switch while said reclosing switch is in closed position.

6. A circuit breaker comprising a circuit interrupting switch biased in an opening direction, a circuit reclosing switch biased in a closing direction and connected in the circuit in shunt relation to said interrupting switch, means for releasably holding the interrupting switch closed and for holding the reclosing switch open, a disconnecting switch connected in the circuit in series relation with the interrupting switch and the reclosing switch, a compressed air operating mechanism for opening and closing said disconnecting switch, control means for simultaneously initiating an opening movement of the interrupting switch and an operation of the operating mechanism to open the disconnecting switch, means operated by the interrupting switch to prevent operation of the operating mechanism until the interrupting switch is open, and means controlled by the reclosing switch to prevent opening of said disconnecting switch while said reclosing switch is in closed position.

7. A circuit breaker comprising a circuit interrupting switch biased in opening direction, a normally open circuit reclosing switch biased in closing direction and connected in the circuit in parallel with said interrupting switch, means for releasably restraining the interrupting switch in closed position and the reclosing switch open, a disconnecting switch connected in the circuit in series relation with the interrupting switch and the reclosing switch, additional restraining means for holding the reclosing switch in open position, operating mechanism for opening and closing said disconnecting switch, control means for simultaneously causing operation of the restraining means to release the interrupting switch, for initiating an opening operation of the operating mechanism, and for rendering the additional restraining means effective to restrain the reclosing switch in open position, means controlled by the interrupting switch to prevent opening of the disconnecting switch until said interrupting switch is opened, and means controlled by the reclosing switch to prevent operation of the operating mechanism when said reclosing switch is closed.

8. A circuit breaker comprising circuit interrupting contacts biased in an opening direction, circuit reclosing contacts biased in a closing direction and connected in the circuit in parallel relation with said interrupting contacts, means for releasably restraining the interrupting contacts in closed position and for restraining said reclosing contacts in open position, additional restraining means operable at times for restraining the reclosing contacts in open position, disconnecting contacts connected in the circuit in series relation with the interrupting contacts and the reclosing contacts, operating means for opening and closing said disconnecting contacts, operating means for closing the interrupting contacts and for opening the reclosing contacts, control means for initiating an opening movement of the interrupting contacts, for causing an operation of the additional restraining means to hold the reclosing contacts in open position, and for causing operation of the disconnecting contacts after the interrupting switch reaches open

position, and means to prevent operation of said disconnecting contacts except when the interrupting contacts and the reclosing contacts are in open position.

9. A circuit breaker comprising circuit interrupting contacts, circuit reclosing contacts connected in the circuit in parallel relation with said interrupting contacts, means for releasably holding the interrupting contacts in closed position and for holding said reclosing contacts in open position, disconnecting contacts connected in the circuit in series relation with the interrupting contacts and the reclosing contacts, operating mechanism for opening and closing said disconnecting contacts, means for causing opening of the interrupting contacts and closing of the reclosing contacts, and control means for causing an operation of the operating means for the disconnecting contacts only after the interrupting contacts are open and before the reclosing contacts close.

10. A circuit breaker comprising circuit interrupting contacts biased open, circuit reclosing contacts biased closed and connected in the circuit in parallel relation with the interrupting contacts, means for releasably holding the interrupting contacts closed and the reclosing contacts open, disconnecting contacts connected in the circuit in series relation with the interrupting contacts and the reclosing contacts, operating means for opening and closing the disconnecting contacts, means for causing opening of the interrupting contacts and closing of the reclosing contacts, and control means for causing the operating means to close the disconnecting contacts only after the interrupting contacts are open and before the reclosing contacts close.

11. A circuit breaker comprising a circuit interrupting switch biased open, a circuit reclosing switch biased closed and connected in parallel with the interrupting switch in the circuit, means for releasably holding the interrupting switch closed and the reclosing switch open, trip means operable when energized to release said switches, holding means including an electromagnet operable when energized to hold the reclosing switch open, a disconnecting switch connected in the circuit in series relation with the interrupting switch and the reclosing switch, operating mechanism for opening and closing said disconnecting switch, a control circuit for simultaneously energizing the trip means to effect opening of the interrupting switch, energizing the holding means to prevent closing of the reclosing switch, and for causing operation of the operating mechanism to effect opening or closing of the disconnecting switch, after the interrupting switch reaches open position, and means to prevent closing of the reclosing switch until the disconnecting switch is fully opened or closed.

12. A circuit breaker comprising a circuit interrupting switch biased open, a circuit reclosing switch biased closed and connected in the circuit in parallel with the circuit interrupting switch, means for effecting opening and closing of said switches, a disconnecting switch, operating mechanism for opening and closing said disconnecting switch, means comprising a plurality of electromagnets operable when energized to cause the operating mechanism to operate the disconnecting switch to its open or closed positions, and means to prevent energization of said electromagnets when either the interrupting switch or the reclosing switch is closed.

13. Electrical circuit controlling apparatus

comprising a circuit interrupter operable to open and automatically reclose the circuit, a disconnecting switch connected in the circuit in series with the circuit interrupter, means operable in response to predetermined abnormal conditions in the circuit to cause said circuit interrupter to open and automatically reclose the circuit, said disconnecting switch remaining closed during operation of said interrupter in response to said abnormal conditions, and control means operable at will to cause opening or closing of said disconnecting switch and to cause said interrupter to open the circuit prior to opening or closing of the disconnecting switch and to maintain the circuit open during operation of said disconnecting switch.

14. Electrical circuit controlling apparatus comprising a circuit interrupting device operable to open and automatically reclose the circuit, operating means for said circuit interrupting device, means operable in response to predetermined abnormal conditions in the circuit to cause operation of said circuit interrupting device to open and automatically reclose the circuit, a disconnecting switch connected in series with said circuit interrupting device, operating means for said switch, and control means for the operating means of said interrupting device and switch operable at will to cause said circuit interrupting means to interrupt the circuit and then cause opening or closing of said disconnecting switch and to maintain said circuit interrupting means in open position at least until operation of said switch has been completed.

15. Electrical circuit controlling apparatus comprising a circuit interrupter operable to open and automatically reclose the circuit, operating means for said circuit interrupter, means operable in response to predetermined abnormal conditions in the circuit to cause operation of the interrupter to open and automatically reclose the circuit, a disconnecting switch in series with said interrupter, operating means for said switch, and control means for jointly controlling the operating means of said interrupter and switch, said control means including a manually operable controller operable to cause said interrupter to open and be maintained open as long as said controller is held in operated position and for causing opening or closing of said switch after said interrupter reaches open position.

16. Electrical circuit controlling apparatus comprising a circuit interrupter operable to open and automatically reclose the circuit, operating means for said circuit interrupter, means operable in response to predetermined abnormal conditions in the circuit to cause operation of the interrupter to open and automatically reclose the circuit, a disconnecting switch in series with said interrupter, operating means for said switch, and control means for jointly controlling the operating means of said interrupter and switch, said control means including a manually operable controller movable to one position to cause the interrupter to open and then the switch to open and movable to a second position to cause the interrupter to open and then the switch to close, said control means causing the interrupter to remain in open position until the operation of said switch has been completed.

17. Electrical circuit controlling apparatus comprising a circuit interrupter operable to open and automatically reclose the circuit, operating means for said circuit interrupter, means operable in response to predetermined abnormal con-

ditions in the circuit to cause operation of the interrupter to open and automatically reclose the circuit, a disconnecting switch in series with said interrupter, operating means for said switch, and control means for jointly controlling the operating means of said interrupter and switch, said control means including a manually operable controller movable to one position to cause the interrupter to open and then the switch to open and movable to a second position to cause the interrupter to open and then the switch to close, said control means maintaining said interrupter in open position as long as said controller is held in either of said positions.

18. Electrical circuit controlling apparatus comprising circuit interrupting means operable in response to predetermined abnormal conditions in the circuit to open and automatically reclose the circuit, operating means for the circuit interrupting means, a disconnecting switch connected in the circuit in series with the circuit interrupting means, operating means for said switch, and control means for jointly controlling the operating means of the circuit interrupting means and switch, said control means being operable to cause the circuit interrupting means to interrupt the circuit and maintain the circuit

temporarily interrupted and to open or close the disconnecting switch during the interval when the circuit is temporarily interrupted at the circuit interrupting means.

5 19. Electrical circuit controlling apparatus comprising a circuit interrupter having a pair of circuit interrupting contacts and a second pair of contacts in parallel therewith for reclosing the circuit, operating means for the interrupter operable in response to predetermined abnormal conditions in the circuit to cause the circuit interrupter to open the circuit by the interrupting contacts and automatically reclose the circuit by said second pair of contacts, a disconnecting switch connected in the circuit in series with the circuit interrupter, operating means for said switch, and control means for jointly controlling the operating means of the interrupter and switch, said control means being operable to cause opening of said circuit interrupting contacts and opening or closing of said switch after the interrupting contacts reach open position and for maintaining said second pair of contacts of the interrupter temporarily open until the operation of said switch is completed.

10 15 20 25 WERNER KAUFMANN.
